US0D1057657S

(12) **United States Design Patent** (10) **Patent No.:** **US D1,057,657 S**
(45) **Date of Patent:** **** Jan. 14, 2025**

(54) **CHARGING DOCK FOR ELECTRIC TOOTHBRUSH**

(71) Applicant: **Shenzhen Bikun Technology Co., Ltd.**, Guangdong (CN)

(72) Inventor: **Junying Wu**, Fujian Province (CN)

(73) Assignee: **Shenzhen Bikun Technology Co., Ltd.**, Guangdong (CN)

(**) Term: **15 Years**

(21) Appl. No.: **29/961,595**

(22) Filed: **Sep. 6, 2024**

(51) **LOC (15) Cl.** **13-02**

(52) **U.S. Cl.**

USPC **D13/108**

(58) **Field of Classification Search**

(57) **CLAIM**

The ornamental design for a charging dock for electric toothbrush as shown and described.

DESCRIPTION

FIG. 1 is a front, right and top perspective view of a charging dock for electric toothbrush, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines in the drawings depict portions of the charging dock for electric toothbrush that form no part of the claimed design.

1 Claim, 8 Drawing Sheets
